United States Patent Office

Des. 175,476
Patented Aug. 30, 1955

175,476

REFUSE CAN

Raymond E. Paddock, Elm Grove, Wis., assignor to New York Shipbuilding Corporation, New York, N. Y., a corporation of New York

Application September 23, 1954, Serial No. 32,409

Term of patent 14 years

(Cl. D58—17)

Fig. 2.

Fig. 1.

Fig. 3.

The rear and side of the can not shown are the same as the front and side shown.

I claim:

The ornamental design for a refuse can, substantially as shown and described.
